UNITED STATES PATENT OFFICE.

ALBERT H. PRICE AND WALTER D. PRICE, OF NEWARK, OHIO.

HARROW.

SPECIFICATION forming part of Letters Patent No. 328,519, dated October 20, 1885.

Application filed April 27, 1885. Serial No. 163,631. (No model.)

To all whom it may concern:

Be it known that we, ALBERT H. PRICE and WALTER D. PRICE, citizens of the United States, residing at Newark, in the county of 5 Licking and State of Ohio, have invented certain new and useful Improvements in Harrows, of which the following is a specification.

Our invention relates to improvements in folding harrows; and it consists in the various 10 constructions and combinations hereinafter described, and pointed out in the claims.

In the accompanying drawings, which form a part of this specification, Figure 1 is a perspective of a harrow embodying our invention, shown folded up ready for transportation. Fig. 2 is a plan view of the same unfolded and 15 ready for use. Fig. 3 is a side elevation view of the same, showing the lifting levers; and Figs. 4, 5, and 6 are detailed views of some of 20 the parts, which will be more particularly referred to hereinafter.

Like parts are indicated by similar letters of reference throughout the several views.

The harrow is composed of the rectangular 25 or square sections A B B', which are connected together, as shown, by the hinge-connections C. On the outer edges of the side or wing sections B and B', respectively, are runners or supporting-bars D D', on which the harrow is supported when folded up, as shown in 30 Fig. 1. The hinged connections C each consist of an arm, a, which is secured at one end to the edge of the middle section, A, and projects outwardly, and is connected to a bifurcated clip, b, which is secured to the inner 35 edge of the wing-section. The joint or hinge is preferably made by means of a rod, c, which extends through an opening in the end of said arm and through the clips b. The connection 40 thus formed permits the wing-sections to turn ninety degrees from the horizontal, or at right angles to the middle section, but is limited against further movement by the connecting-arm a coming into contact with the base of 45 the bifurcated clip b, as shown in Fig. 6.

In order to provide for raising the respective sections, as desired, to remove any débris which may collect therein, or for other purposes, we provide lifting-levers E E', which are 50 supported on the middle section, A, and connected by suitable means to the side or wing

sections, B B'. These levers are each connected at one end to a standard, F F', at the front of the middle section by means of a slotted connecting-piece or yoke, d. The standards F F' have each an elongated head, e, adapted to pass through the slotted piece or yoke d, when said yoke is turned parallel thereto, as indicated by dotted lines in Fig. 4, said yoke being held from coming off of 55 said standard by the elongated head when turned to its normal position, as shown in full lines in Fig. 4. The levers E E' extend backwardly from the standards F F', and are supported at the rear of the harrow in bifurcated 60 supports G, which project upwardly from the middle section, A.

The fork projections f f of the bifurcated standards or supports G are each constructed in the form of a hook, and are adapted to be 70 engaged when the lever is raised vertically therein by a projecting pin or pins, g, secured in the lever. (See Fig. 5.) The projecting pins g are so placed in the lever E that when the lever is in its normal position in the support G the said projecting pins stand below the point of the hooks in projections f f, so that by a longitudinal movement of the said lever the pins may be moved from under said hooks, and thus permit the lever to be raised 80 out of the supporting-piece without engaging said hooks. This longitudinal movement of the lever is permitted by the slotted piece or yoke d, by which it is connected to standard F.

The levers E E' are respectively connected, 85 preferably by means of chains H H', to the side sections, B B', as shown, so that when either of said levers is raised out of the supporting-piece G, as indicated by dotted lines in Fig. 3, the section connected thereto may 90 be readily raised from the ground and turned on its hinged connections by a lateral movement of the said lever.

If it is desired to raise the middle section the levers are dropped into the bifurcated supports and moved longitudinally forward until the projecting pins g come under the hooks on the fork projections f f, when, by a vertical movement of the levers, the pins g will engage said hooks, and thus raise the harrow. 95

When it is desired to fold the harrow for transportation, the harrow is raised up on its 100

front end, the chains H H' unhooked from the lifting-levers, and the side or wing sections turned in at right angles to the middle sections, after which the inner ends of the chains 5 H H' are attached to hooks h h' at the middle of the middle section, A. The harrow is then turned over onto the runners D D', the hitch is made to rings i i', secured to the edges of sections B B', at the front ends of runners D D', 10 and the harrow is ready for transportation.

It will be seen that by making the sections square or rectangular, as shown, and folding the side or wing sections inwardly, as described, the middle section will be elevated 15 equally at both ends to a distance from the ground equal to the width of the side sections, so that it may readily pass over ordinary obstructions without danger to the teeth of the harrow.

20 The hinged or side sections are held from turning inwardly by the hinged connection, as described, and from turning outwardly by the chains H H'. The teeth being all turned inward are protected from injury, and at the same time are less dangerous to cattle or stock 25 when the harrow is left standing in the field.

By having the side sections to fold inwardly at right angles to the middle section we are enabled to place the metallic runners D D' on 30 the outer edges of the side sections and in the same horizontal plane therewith, thus leaving the top of the sections free, and at the same time bringing the weight of the runners or supports where it is most needed.

35 The lifting-levers, it will be seen, are attached to and supported entirely from the middle section, so that they need not be disturbed or changed when the harrow is folded. They are at the same time readily detachable, and 40 may be removed or replaced at will.

Having thus described our invention, we claim—

1. The combination, in a folding harrow, of

a middle section having side or wing sections hinged thereto, said side or wing sections being rectangular in shape and provided on their outer edges with supporting-runners on which the harrow is adapted to rest by folding said side sections inwardly at right angles to the middle section, and thus raise said middle 45 section equally at both ends for transportation, substantially as specified.

2. The combination, with the lifting-lever provided with the slotted connecting piece or loop and with a projecting pin or pins, of the 50 standard having an elongated head and the bifurcated support having hooked projections, and means for connecting said levers to the movable or hinged section, substantially as 55 set forth.

3. The combination, with the middle and side sections, of the lifting-lever adapted to be connected at one end by a slotted connecting piece or loop to a standard provided with an elongated head on said middle section, a support for the rear end of said lever, and means for connecting the said levers to the side sections, substantially as described and 60 shown.

4. The combination, with the stationary 70 middle section having the lifting-levers thereon, of hinged movable sections having chains connected to the outer edges thereof, said chains being adapted to be connected to the said levers when the harrow is unfolded and 75 to the middle section when the harrow is folded, substantially as and for the purpose set forth.

In testimony whereof we have hereunto set our hands this 16th day of April, A. D. 1885.

ALBERT H. PRICE.
WALTER D. PRICE.
